REMOTE CONTROLS MOUNTED ON MOBILE CARRIAGES

Hiram Y. Hallock, Madison, Wis., assignor to Jackson Lumber Harvester Company, Inc., Brewton, Ala., a corporation of Alabama

Application March 8, 1955, Serial No. 493,001

12 Claims. (Cl. 143—105)

This invention relates to improvements in remote controls mounted on movable carriages.

Certain types of devices such as sawmills may employ a reciprocating carriage on which the work is mounted, the carriage being driven by a prime mover located in fixed position on the frame. On those devices where an operator rides on the carriage it is highly desirable to have a simple form of control for readily controlling the direction of operation and the speed of the prime mover from a position on the carriage. Such control must also be operable while the carriage is moving so that its direction of movement can be reversed when required. To accomplish this with simple mechanism which eliminates the necessity of using dangling hydraulic conduits or the like, presents problems.

It is a general object of the present invention to provide in a device of the class described, novel means operable from a position on the carriage for controlling the direction of operation of the prime mover as well as the speed thereof to thereby control the direction and speed of movement of the carriage.

A further object of the invention is to provide in a device of the class described, control mechanism for a motor which is positioned on a fixed frame, which control mechanism includes cable means extending along the frame together with a control unit on the carriage through which the cable means is guided as the carriage moves along with respect to the cable means and frame, said control unit being operable from a position on the carriage to exert a force on the cable in one direction or the other, even when the carriage is moving, to thereby control the direction of operation and speed of the motor and hence the direction of movement and speed of the carriage.

A more specific object of the invention is to provide control mechanism as above described which is particularly well adapted for use in a device having an hydraulic motor and valve mounted on the fixed frame, there being means on the carriage operable even when the carriage is moving for actuating said valve to thereby control the flow of fluid to the hydraulic motor and hence the direction and speed of movement of the carriage.

With the above and other objects in view, the invention consists of the improvements in controls mounted on movable carriages, and all of its parts and combinations, as set forth in the claims, and all equivalents thereof.

In the accompanying drawing, illustrating several preferred embodiments of the invention, in which the same reference numerals designate the same parts in all of the views:

Fig. 1 is a side elevational view showing the invention applied to a sawmill of the type having a reciprocating carriage, parts being broken away and shown in section;

Fig. 2 is a top view of the sawmill, part of the carriage platform being broken away;

Fig. 3 is a fragmentary plan view showing the control

elements in a position to operate the carriage in a reverse direction from that of Fig. 2;

Fig. 4 is a transverse sectional view taken on the line 4—4 of Fig. 2;

Fig. 5 is a view looking at the bottom of the control disc as indicated by the line 5—5 of Fig. 1;

Fig. 6 is a fragmentary plan view, partially diagrammatic, showing a modified form of control unit;

Fig. 7 is a similar view showing another modified form 10 of control unit; and

Fig. 8 is a similar view showing still another modified form of control unit.

Referring now more particularly to the drawing, the numeral 10 designates a fixed frame which may include 15 side sections 11 and 12 suitably connected in spaced-apart condition by transverse members 13, 14 and 15. Projecting laterally from the side 11 is an extension frame 16 which supports bearings 80 for the drive shaft 81 of a circular saw 18', the saw being driven by a sprocket 20 chain 32 or the like from any suitable source coaxing with the sprocket wheel 83 on the saw shaft 81. The extension 16 also supports a motor 19 which may be of any desired type. The present invention, however, is well suited for use in connection with an hydraulic motor and the numeral 19 therefore designates such hydraulic motor.

Hydraulic fluid from the reservoir 20 may be circulated by an hydraulic pump 21 through a line 22 to an hydraulic control valve 23. The valve is operated by an 30 oscillatable lever 24 mounted on a shaft 25. This valve may be of any well known type. When the lever 24 is in a vertical central position the valve will cause fluid from the pump to be by-passed back to the reservoir through line 26 without causing any operation of the 35 hydraulic motor 19. When the valve lever 24 is in the position of Figs. 2 and 4, then fluid will flow to the motor through line 27 and will be returned through line 28 to the valve and then through line 26 back to the reservoir. This will cause operation of the motor in one direction.

40 When the control valve lever 24 is in the position of Fig. 3, then fluid under pressure from the pump 21 will flow out of the valve through the line 28 to the hydraulic motor 19 to operate the latter in a reverse direction, and will be returned through the line 27.

45 Journalled transversely of the frame is a carriage drive shaft 29 which carries a sprocket wheel 30 on its outer end. The sprocket wheel 30 may be connected by an endless chain 31 with a sprocket wheel 32 mounted rigidly on the motor shaft 18. Mounted rigidly on the 50 shaft 29 is a drum 33. A cable 34 has one end connected as at 35 to the end of the carriage 36. The cable then extends longitudinally of the frame and passes around a suitably mounted pulley 37. From the underside of 55 the pulley the cable extends to the drum 33 and may be wrapped a number of times around the drum. On the other side of the drum the cable extends to the underside of a pulley 37' and up around the latter, the end of the cable being fastened to the rear end of the carriage as at 38. It is thus apparent that when the drum 33 is 60 rotated that the carriage will be moved in one direction or the other along the frame 10, depending upon the direction of rotation of the drum.

The upper rails of the side sections 11 and 12 carry 65 rollers 39 which are suitably mounted. The feed carriage 36 may have depending side flanges 40 which embrace the rollers 39, the carriage being movable over the rollers in a direction longitudinally of the frame 10, as is clear from Figs. 1 and 2. The feed carriage may have a platform 41 on which an operator may stand.

70 Suitably supported on an intermediate transverse carriage member 42 and projecting above the carriage 36 is a sleeve 43. A similar sleeve 44 depends from the under-

side of the transverse member 42. Suitably journaled in the sleeves 43 and 44 is a vertical shaft 45 having its lower end projecting from the bottom of the sleeve 44 and carrying a control disc 46. The upper end of the shaft 45 has a manually operable control handle 47 rigidly connected thereto.

Rotatably mounted on the control disc 46 are sets of pulleys 48 and 49, the pulleys being preferably mounted near the periphery of the disc 46 and being spaced 90° apart.

A control cable 50 has one end anchored to a spring at the frame as at 51. This cable is guided around the pulleys 48, as shown in Fig. 2, and extends forwardly where it passes around a pulley 52 at the far end of the frame, as shown in Fig. 2. The cable extends in a reverse direction and passes around a pulley 53 which is suitably supported at an intermediate position. From the pulley 53 the cable extends in a direction transversely of the frame and is connected to the control lever 24 of the valve 23, as is shown in Fig. 4.

Another control cable 55 has one end anchored to a spring at the frame as at 151. The cable 55 is guided around the other set of pulleys 49 of the control disc and then extends longitudinally to the far end of the frame where it extends around a pulley 56 and then in a reverse direction to an intermediate pulley 57. From the pulley 57 the cable extends transversely of the frame to connect with the control lever 24 for the valve 23.

In operation, if the operator wishes to have the carriage move in a feed direction, the operator on the platform 41 will move the handle 47 to the position of Fig. 2. Due to the position of the pulleys 49 when the handle is in the position of Fig. 2, this will exert a pull on the control cable 55 swinging the valve lever 24 to the full line position of Fig. 4, and allowing hydraulic fluid under pressure from the pump 21 to pass through the control valve 23 to the hydraulic motor 19 in a direction to cause forward feed movement of the carriage 36, the saw being independently rotated in the direction indicated by the arrow in Fig. 1.

After the carriage has completed its feed stroke the operator on the platform can shift the control unit handle 47 to the position of Fig. 3. This will cause a slackening of the cable 55 but instead will move the pulleys 48 to the position of Fig. 3 to exert a pull on the cable 50. This will move the valve lever 24 to the dot and dash line position of Fig. 4. As a result the direction of flow of hydraulic fluid to the hydraulic motor 19 will be reversed and hence the direction of rotation of the drum 33 will be reversed to cause the carriage to be moved in a return direction. In either direction of operation, by moving the control handle 47 to less extreme positions the amount of fluid flow to the hydraulic motor may be reduced to thereby control the speed of operation as desired. When the control handle 47 is in a position parallel to the frame 10, then the lever 24 for the valve 23 is held in a neutral position. When in this position, hydraulic fluid from the pump 21 is returned directly from the valve 23 back to the reservoir 20 through line 26, without causing operation of the motor 19.

In the modification of Fig. 6, a control unit 60 on the transverse member 42 of the carriage is used. Slidable in a groove 61 of the control unit 60 is an operating bar 62 which may be suitably moved from a position on the carriage. The operating bar 62 carries rotatably mounted pulleys 63 and there are sets of pulleys 64 and 65 on the control unit 60. The control cable 50 is guided around the pulleys 65 and 63 in the manner shown, and the control cable 55 is guided around the pulleys 64 and 63, as illustrated. As a result of this arrangement, if the control bar 62 is moved toward the top of the sheet, there will be a slackening of the cable 55 and a pull on the cable 50 to shift the valve lever 24 to the position shown by full lines in Fig. 4. When the bar is in the position shown in Fig. 6, it is in neutral. When it is moved toward the bot-

tom of the sheet the cable 50 is slackened and a pull is exerted on the cable 55.

The operation of the form of the invention of Fig. 7 is substantially the same, parts corresponding to those of Fig. 6 being primed. In Fig. 7 the control bar 61 is shown in neutral. If it is slid toward the top of the sheet the cable 50 will be slackened and there will be a pull on the cable 55 to shift the control lever 24 to the dotted line position of Fig. 4. Movement of the control bar 62' in the reverse direction causes a reverse operation of the control lever 24.

In the modification of Fig. 8 a fixed bar 66 may be suitably mounted on the transverse frame member 42 of the carriage. Pivoted to the bar 66 as at 67 are parallel links 68. A T-shaped operating handle 69 has its ends pivoted to the links 68. Pulleys 70 are rotatably mounted on one of the links 68 and pulleys 71 are rotatably mounted on the other link 68. Movement of the control handle 69 in the direction indicated by the arrows will cause a

slackening of the cable 55 and a pull on the cable 50 to shift the valve lever 24 to the full line position of Fig. 4. Movement of the handle 69 in a reverse direction to that of the arrows will exert a pull on the cable 55 and will cause a reverse operation of the valve.

It is apparent that the present invention provides a very simple remote mechanical control for the valve of a fluid control assembly without the necessity of having fluid hoses moving with the carriage. The control system may be employed to shift any type of lever on the fixed frame, and its utility is therefore not limited to use with the particular hydraulically operated mechanism shown.

Various changes and modifications may be made, as well as other adaptations without departing from the spirit of the invention, and all of such changes and adaptations are contemplated, as may come within the scope of the claims.

What I claim is:

1. In combination a frame, a carriage mounted for movement on said frame, a motor on said frame, transmission means between said motor and carriage for transmitting motion to the latter, means controlling the operation of said motor including cable means extending along said frame independently of said transmission means, a control unit on said carriage through which said cable means is guided as the carriage moves along with respect to said cable means and frame, said control unit having manually operable means on the carriage which is movable to exert a force on said cable means without interfering with the movement of the carriage relative to said cable means to control said motor and hence the movement of said carriage.

2. In combination a frame, a carriage mounted for reciprocating movement on said frame, a driven rotatable member on said frame, means including an elongated flexible member connected between said rotatable member, frame and carriage for transmitting motion to the carriage, means independent of said flexible member for controlling the direction of operation of said rotatable member including a control element on the frame and including cable means extending along said frame and connected at one end to the frame and at the other end to the control element, a control unit on said carriage through which said cable means is guided as the carriage moves

along with respect to said cable means and frame, said control unit having manually operable means on the carriage which is movable to alter the effective length of said cable means and thus move said control element to control the direction of rotation of said rotatable member, and hence the direction of movement of said carriage.

3. In combination a frame, a carriage mounted for reciprocating movement on said frame, a motor on said frame, transmission means between said motor and carriage for transmitting motion to the latter, means for controlling the direction of operation of said motor in-

cluding cable means extending along said frame independently of said transmission means, a control unit on said carriage through which said cable means is guided as the carriage moves along with respect to said cable means and frame, said control unit having manually operable means on the carriage which is movable to exert a force in a selected direction on said cable means without interfering with the movement of the carriage relative to said cable means to control the direction of operation of said motor and hence the direction of movement of said carriage.

4. In combination a frame, a carriage mounted for reciprocating movement on said frame, a motor on said frame, transmission means between said motor and carriage for transmitting motion to the latter, means for controlling the speed and direction of operation of said motor including cable means extending along said frame independently of said transmission means, a control unit on said carriage through which said cable means is guided as the carriage moves along with respect to said cable means and frame, said control unit having manually operable means on the carriage which is movable a selected amount in a selected direction to exert a force on said cable means without interfering with the movement of the carriage relative to said cable means to control the speed and direction of operation of said motor and hence the speed and direction of movement of the carriage.

5. In combination a frame, a carriage mounted for reciprocating movement on said frame, a motor on said frame, transmission means between said motor and carriage for transmitting motion to the latter, means for controlling the direction of operation of said motor including two cables extending along said frame independently of said transmission means, a control unit on said carriage through which said cables are guided as the carriage moves along with respect to said cables and frame, said control unit having manually operable means on the carriage which is movable to exert a force on one or the other of said cables without interfering with the movement of the carriage relative to said cable means to control the direction of operation of said motor and hence the direction of movement of the carriage.

6. In combination a frame, a carriage mounted for movement on said frame, a motor on said frame, transmission means between said motor and carriage for transmitting motion to the latter, means for controlling the operation of said motor including cable means extending along said frame independently of said transmission means, a control unit on said carriage including rotatably mounted pulleys around which said cable means is guided as the carriage moves along with respect to said cable means and frame, said control unit having manually operable means on the carriage which is movable to shift the position of said pulleys and exert a force on said cable means without interfering with the movement of the carriage relative to said cable means to control said motor and hence the movement of the carriage.

7. In combination a frame, a carriage mounted for movement on said frame, a motor on said frame, transmission means between said motor and carriage for transmitting motion to the latter, means controlling the operation of said motor including cable means extending along said frame independently of said transmission means, a control unit on said carriage including a rotatably mounted disk having rotatable pulleys thereon around which said cable means is guided as the carriage moves along with respect to said cable means and frame, said control unit including means on the carriage for rotating said disk to shift the position of the pulleys thereon and exert a force on said cable means without interfering with the movement of the carriage relative to said cable means to control said motor and hence the movement of said carriage.

8. In combination a frame, a carriage mounted for reciprocating movement on said frame, a fluid pressure

operated motor on said frame, transmission means between said motor and carriage for transmitting motion to the latter, means for delivering fluid under pressure to said motor including a control valve on the frame having an operating lever, cable means independently of said transmission means connected to said valve lever and extending along said frame and connected thereto, a control unit on said carriage through which said cable means is guided as the carriage moves along with respect to said cable means and frame, said control unit having manually operable means on the carriage which is movable to exert a force on said cable means without interfering with the movement of the carriage relative to said cable means to shift said valve lever.

15 9. In combination a frame, a carriage mounted for reciprocating movement on said frame, a fluid pressure operated motor on said frame, transmission means between said motor and carriage for transmitting motion to the latter, means for delivering fluid under pressure to said motor including a control valve on the frame having an operating lever, two cables independently of said transmission means extending along said frame, means for connecting said cables to said valve lever and to said frame to act in opposite directions on said valve lever, 20 a control unit on said carriage through which said cables are guided as the carriage moves along with respect to said cables and frame, said control unit having manually operable means on the carriage which is movable to exert a force on one or the other of said cables without interfering with the movement of the carriage with respect to said cables to shift said valve lever in a selected direction.

30 10. In combination a frame, a carriage mounted for reciprocating movement on said frame, a driven rotatable member on said frame, means including an elongated flexible member connected between said rotatable member, frame and carriage for transmitting motion to the carriage, means independent of said flexible member for controlling the direction of operation of said rotatable 35 member including a pivotally mounted lever on the frame, cable operating means connected at one end to said lever and at the other end to said frame and extending along said frame, a control unit on said carriage through which said cable means is guided as the carriage moves along with respect to said cable means and frame, said control unit having manually operable means on the carriage which is movable to alter the effective length of said cable means to shift said lever.

45 11. In combination a frame, a carriage mounted for reciprocating movement on said frame, a motor on said frame, transmission means between said motor and carriage for transmitting motion to the latter, means for controlling the direction of operation of said motor including a pivotally mounted operating lever on the frame, 50 cable operating means connected to said lever and extending along said frame independently of said transmission means, a control unit on said carriage through which said cable means is guided as the carriage moves along with respect to said cable means and frame, said control unit having manually operable means on the carriage which is movable to exert a force on said cable means to shift said lever without interfering with the movement of the carriage relative to said cable operating means.

55 12. In combination a frame, a carriage mounted for reciprocating movement on said frame, a motor on said frame, means between said motor and carriage for transmitting motion to the latter, means independent of said last means for controlling the direction of operation of said motor including a control element for said motor and 60 including two cables extending along said frame and connected at one end to the frame and at the other end to the control element, a control unit on said carriage including a rotatably mounted disk having two pairs of rotatable 65 pulleys thereon, the individual pulleys of each pair being 70 75 pulleys, the individual pulleys of each pair being

oppositely disposed on the disk, one of said cables being guided around the pulleys of one pair and the other cable being guided around the pulleys of the other pair as the carriage moves along with respect to said cables and frame, said control unit including means on the carriage for rotating said disk to shift the position of the pulleys thereon and exert a force on one or the other of said cables to thus move the control element and control the direction of said motor and hence the direction of movement of said carriage.
